UNITED STATES PATENT OFFICE.

ALFRED W. MORGAN, OF INDIANAPOLIS, INDIANA, ASSIGNOR TO LOUISA G. MORGAN, OF SAME PLACE.

FORGE-TUYERE.

SPECIFICATION forming part of Letters Patent No. 250,161, dated November 29, 1881.

Application filed April 19, 1881. (No model.)

To all whom it may concern:

Be it known that I, ALFRED W. MORGAN, a citizen of the United States, residing at Indianapolis, in the county of Marion and State 5 of Indiana, have invented a new and useful Adjustable Variable-Blast Tuyere-Iron for Blacksmiths, of which the following is a specification.

My invention relates to improvements in 10 tuyere-irons in which a rotatable center piece having different-sized radial nozzles operates in conjunction with a tuyere-iron case having a detachable head with tuyere-holes above and a dirt-trap below; and the objects of my 15 invention are, first, to provide a tuyere-iron with an adjustable and variable conductor for the blast, by means of which a large fire for heavy work or a small one with an intense heat for small work may be kept up; second, 20 to afford facilities for adjusting the variable blast-conductor, to produce any size fire required; and, third, to provide a means for discharging cinders and dirt from the tuyere-iron shell and dirt-trap below. These objects 25 I accomplish by the mechanism illustrated in the accompanying drawings, in which—

Figure 1 represents a vertical longitudinal section of the entire machine. Fig. 2 is an 30 end elevation of the same. Fig. 3 is an elevation of the rotatable adjustable variable blast-conductor; and Fig. 4 is a plan view of the 35 indicator hand-wheel for operating the variable blast-conductor, showing the spokes of various sizes corresponding with their respective various-sized nozzles in the rotatable blast-conductor.

Similar letters in the different views refer to like parts.

A represents a cylindrical case having an 40 opening, w , in its top to receive the tuyere-head B, also an opening, w' , below, which forms a connection with the blast-pipe E at the side, and the dirt-chamber F below. The dirt-chamber F has a hole, H, in its bottom, which is 45 closed automatically by the ball-valve G.

Inside of the cylindrical shell A is the rotatable adjustable variable blast-conductor C, which may be made with two or more nozzles. In the case illustrated four nozzles are used,

radiating from the center. These nozzles are 50 constructed as shown—that is, the nozzle C' is large enough to distribute a blast through all the tuyere-holes a a' a^2 a^3 in the head B, while the nozzle C² is enough smaller as to only discharge the air through the tuyere-holes 55 a' a^2 a^3 . The nozzle C³ is small enough to discharge the air through the tuyere-holes a^2 a^3 , and the nozzle C⁴ discharges the air only through the center tuyere-hole, a^3 . All the nozzles C' C² C³ C⁴ form branches of one common chamber, and the ends of the nozzles are turned in a lathe, so as to fit snugly within the case, yet loosely enough to permit the blast-conductor to be turned freely for adjustment within said case. Thus when the nozzle C² is 60 over the opening w' of the case A the nozzle C' is free to discharge air through all the tuyere-holes of the head B; but when the nozzle C' is over the hole w' , then the nozzle C² discharges the air through the holes a' a^2 a^3 , as 65 before described. Thus as each nozzle C' C² C³ C⁴ is brought opposite the tuyere-holes in the head B air is discharged relative to the size of the nozzle. Between the nozzles C² and C⁴ is a segment-rim, D, which, when adjusted 70 over the hole w' , forms a cut-off and permits the dirt and cinders which may accumulate in the dust-chamber F to be discharged through the opening H when the valve G is raised and the blast applied through the pipe E. All 75 dirt which may fall into the cylinder A is wiped into the hole w' by the nozzles as the blast-conductor is turned around. When the chamber F needs cleaning, the ball-valve G is raised and the dirt blown out, as before described.

The rotatable blast-conductor C has trunnions K K', one on each side, the trunnion K' operating in a socket formed in the solid head of the cylinder A, while the trunnion K', which has a square hole, k, in it, operates in the cylinder-head A'. The cylinder-head A' is secured to the cylinder by bolts g g, made fast in the lugs f f'. The square rod J fits in the hole k of the trunnion K, also in the square hole I of the indicator-wheel L. The wheel L has spokes C⁵ C⁶ C⁷ C⁸. Each spoke varies in size to indicate the position of its respective nozzle.

Thus when the spoke C⁵ is turned up it indicates that the largest nozzle C' is in position under the tuyere-holes. The spoke C⁶ when turned up indicates that the nozzle C² is under the tuyere-holes, and so on with the other spokes and nozzles.

The head B may be a solid one with tuyere-holes, or a water-jacket head having a chamber around the tuyere-holes to contain water, o as shown in Fig. 1, in which B represents the head, B' the inlet for water, B² the outlet, and B³ the chamber surrounding the tuyere-holes to contain water, for preventing the tuyere-head from burning.

5 What I claim as new, and desire to secure by Letters Patent, is—

- 1. In a tuyere-iron, the cylinder A, with blast-pipe E and dust-chamber F, combined with the head A' and bolts g g, substantially as o shown and described.
- 2. In a tuyere-iron, the cylinder A, combined with the rotatable adjustable variable blast-conductor C and the head B, with tuyere-holes, substantially as shown and described.
- 5 3. The rotatable adjustable variable blast-conductor C, constructed with trunnions K K' and various-sized radiating nozzles, substantially as shown and described.

4. The rotatable adjustable variable blast-conductor C, having a segment-rim, D, between 30 two nozzles, substantially as shown, for the purpose specified.

5. The rotatable adjustable variable blast-conductor C, having its trunnions K, provided with a hole, k, combined with the rod J and 35 indicator hand-wheel L, having spokes C⁵ C⁶ C⁷ C⁸, of several sizes, each size spoke indicating the size of nozzle of the blast-conductor C which is in line with it, substantially as shown and described. 40

6. In combination with the tuyere-iron case, consisting of the cylinder A, blast-pipe E, and dust-chamber F, the ball-valve G, the variable blast-conductor C, and head B, with tuyere-holes a a' a² a³, substantially as shown and 45 described.

In testimony whereof I have signed my name to this specification in the presence of two subscribing witnesses.

ALFRED W. MORGAN.
